LOCK FOR ELEVATOR DOORS

Harry H. Vanderzee, Michigan City, Ind., assignor to Westinghouse Electric Elevator Company, Jersey City, N. J., a corporation of Illinois

Application January 28, 1938, Serial No. 187,503

2 Claims. (Cl. 187—31)

My invention relates to elevator door locks and more particularly to door locks disposed to be operated by cam devices on the elevator cars.

One object of my invention is to provide an elevator door lock which shall have a small number of parts, which shall be simple and inexpensive in construction and which may be easily installed, operated and maintained in operation.

Another object is to provide a lock which shall safely interlock the control circuits of the car to prevent movement of the car whenever the lock fails to operate or the door is not closed and locked.

A further object is to provide a door lock which will not require the use of springs for controlling its operation.

For a better understanding of the invention reference may be had to the accompanying drawing, in which:

20 Figure 1 is a view in front elevation of a door lock embodying my invention, the front cover being removed to expose the inner parts of the lock,

Fig. 2 is a view in side elevation of the lock shown in Fig. 1 with the body of the lock shown in cross-section along the line II—II of Fig. 1,

Fig. 3 is a top plan view of the lock shown in Fig. 1 as installed on a side opening corridor door for an elevator, and

25 Fig. 4 is a slightly enlarged view in side elevation of the locking hook shown in Fig. 2, with part of the insulation thereon broken away.

Referring more particularly to the drawing, I have illustrated a door lock 9 as having a hollow rectangular box or casing 10 provided with a cover 11 which may be secured to the front of the box by a plurality of machine screws 12. The casing is provided with an upper lug 13 and a lower lug 13a having holes 14 by means of which it may be secured to a door frame 15 by means of suitable bolts 16. The lock 9 is shown (Fig. 3) as mounted on the door frame 15 in position to serve a side opening door 18 (only a small portion of which is shown in section).

30 The door is provided with a locking bracket 20 which is secured to the side of the door by suitable screws 21. On the outer end of the bracket is mounted a hook member 22 disposed in position to pass through an aperture 23 in the door jam and enter the lock 9 when the door is closed. The hook 22 may be an integral part of the bracket or it may be constructed of any suitable metal and be welded to the bracket as at 24 by any suitable welding means. The hook member 35 is provided with a downwardly extending projec-

tion or hook 25 disposed to be secured in the lock by a locking latch 26 when the door is in its closed position and the locking mechanism is actuated to lock the door.

The latch 26 constitutes a projecting portion of 5 a lock spindle 27 mounted upon and fixed to a horizontal shaft 28 rotatably mounted in a pair of bearings 29 and 30 in opposite sides of the casing 10. A machine screw 31 passes through the spindle 27 and the shaft 28 to cause the 10 spindle and the locking latch thereon to rotate with the shaft when it is operated to lock or unlock the door.

An operating arm 33 is mounted upon the shaft 28 by means of a bolt 34 and has upon its outer end a roller 35 disposed to be engaged and operated by a cam 36 mounted upon the elevator car (not shown) when the car is to make a stop at the door at which the lock is located. Inasmuch as cam operated arms of this nature are old and well known in the art and any suitable cam and arm will be satisfactory, no further detailed description thereof will be given. However, it will be obvious that when a car comes into the floor and its locking cam is projected to engage the 25 roller 35, the shaft 28 will be rotated by the inward movement of the arm 33 to move the locking latch 26 downwardly and thus free the hook 20 30 25 to permit it to be withdrawn from the lock when the door 18 is opened.

The spindle 27 is provided with a projecting member 37 disposed to engage a lug 38 mounted on the interior of the casing 10 to limit the upward movement of the latch 26 and the outward movement of the arm 33, as desired. It will be observed that the distribution of the weight of the arm 33 and the weight of the latch 26 is such that the latch will be retained in its locking position by the weight of the arm unless the arm is forceably raised and hence no springs are 35 necessary to hold the latch in its locking position when it is not being operated to move to its unlocked position.

The limiting extension 37 is also extended horizontally toward the left-hand side of the casing 45 (see Fig. 1) so that a key (not shown) may be inserted through a key-hole 40 in the lower rear portion of the casing 10 and the face of the door jamb. If a key is pushed through the aperture 40 into engagement with the extension 37, it will cause the latch 26 to move downwardly out of its locking position without the necessity of operating the arm 33. This is to permit the elevator attendant or the repairmen to open the door when necessary. An escutcheon plate 41 is 50 55

mounted on the door jamb to protect and decorate the aperture 40.

In order to prevent operation of the car while the door is open or while it is closed but unlocked, I have provided a pair of interlocking switches 44 and 45 which may be so connected in the control system of the car that the car cannot be operated as long as either one of these switches is open.

10 The switch 44 comprises a pair of contact members 46 and 47 disposed to be connected by a contact plate 48 when the door is closed. The contact plate 48 is mounted upon an insulating block 49 secured to an insulating sleeve 50 mounted upon the hook member 25. The insulating member 50 may be readily constructed by taking a block of suitable fibrous material impregnated with a phenolic condensation product, such as is sold under the trade-mark "Micarta", 15 and sawing a slot in its underside so that it may be placed astraddle the curved upper portion of the hook member 22. A suitable screw 51 is provided for holding the insulator 50 on the hook member and a suitable screw 52 is provided for holding the plate 48 and block 49 on the end portion of the insulator 50. The contact members 46 and 47 are mounted respectively upon a pair of spring contact arms 53 and 54 disposed in suitable slots 55 in an insulating block 56 20 which is secured by a pair of screws 57 upon the face of a supporting lug 58 extending inwardly from the rear wall of the casing 10. The contact arms 53 and 54 are maintained in position by binding posts 70 and 71. By this construction 25 it will be seen that when the door 18 is in its closed position, the hook member 22 presses the contact plate 48 against the contact members 46 and 47 and thereby completes a circuit through the contact arms 53 and 54. Likewise, 30 when the door is opened, the contact plate 48 is withdrawn from the contact members 46 and 47, thereby opening the circuit through the contact arms 53 and 54.

The switch 45 is disposed to be operated by the locking arm 26 and comprises a contact plate 46 45 and a pair of cooperating contact members 63 and 64. The contact plate 62 is mounted upon an insulating block 62a disposed upon the upper end of a switch arm 65. A screw 66 is provided for holding the plate and block in position 50 on the arm. The arm is mounted at its lower end on a projecting portion 73 of the spindle by a screw 67 and by the machine bolt 31 which passes through the arm as well as through the shaft 28. The contact members 63 and 64 of 55 the switch are mounted upon a pair of spring contact arms 63a and 64a which are disposed in suitable slots 55 in the insulating block 56 and secured in position by binding posts 68 and 69.

60 By this construction it will be seen that when the car comes to a stop at the floor and moves its cam 36 against the roller 35, the arm 33 rotates the shaft 28 to release the locking latch 26 from its locking position. The rotation of the shaft moves the arm 65 (Fig. 2) in a clockwise direction which removes the plate 62 from its engagement with the contact members 63 and 64, thereby opening the switch 45 when the door is unlocked. It will also be apparent that when the 65 car cam is removed from the roller, the weight of the roller and the operating arm causes them to rotate the shaft in a counter-clockwise direction (Fig. 2), thereby moving the latch into its locking position and at the same time closing 70 the switch 45.

It will be observed that the insulating block 56 is provided with rather deep slots in which the contact arms are mounted and is itself mounted on the free end of the extension 58 in the lock casing so as to afford long creepage paths between the live contact arms when the switches are closed, but, in order to further provide against short circuits in the lock, I have placed upon each side wall an insulating sheet 81 and upon the inside of the cover 11, an insulating sheet 82. The sheets are secured to the interior of the casing walls and the cover by means of suitable rivets 83. By reason of the insulating sheets and the insulating block, the switch parts are so completely separated from each other and from the walls of the casing that there will be no danger of short circuits in the lock at any time.

If desired, the contact arms of each switch may be connected to different portions of the control circuit (not shown) by connecting the conductors 60 and 60a to the binding posts 68 and 69 and the conductors 60b and 60c to the binding posts 70 and 71, so that one switch will control one section or element in the control circuit and the other switch will control another section or element in the control circuit.

However, if desired, the switches may be connected in series in the control circuit by eliminating the conductors 60 and 60c and connecting the binding posts 68 and 71 by a bridging plate 75 as shown in dotted lines.

By reason of the foregoing operation of the switch 44 by the hook on the door and the operation of the switch 45 by the locking latch, it will be apparent that one of the switches will be open whenever the door is open or the lock is released; that both of the switches will be open when the lock is released and the door is opened, and that consequently the car cannot be operated unless the door is both closed and locked in closed position.

In some elevator installations it may be inconvenient to use the lock shaft, arm and roller mounted and supported by the lock as has heretofore been the usual custom, because it may be desirable to have a much longer shaft 28 than is feasible with mounting it only in the bearings in the lock. Where it is desired to have the operating arm 33 disposed some distance from the lock, I have provided an extension shaft 28a having its one end connected to the outer end of the shaft 28 by means of an extension coupling 76, and having its end rotatably supported in a bearing 77 in the outer end of a supporting bracket member 78. The bracket 78 may be mounted upon the hatchway wall 79 in any suitable manner as by a plurality of bolts 80. With this construction the arm 33 may be mounted upon the extension shaft 28a instead of upon the shaft 28 and, when it is rotated by the action of the car stopping at the floor, the fixed extension coupling 76 will cause the shaft 28 to rotate with the shaft 28a and thereby move the locking latch 26 to its unlocked position. It will be readily understood that the bracket 78 will support the outer end of the extension shaft 28a and that that shaft will in turn support the outer end of the shaft 28 by means of the coupling 26 so that the shaft will be supported in a safe working position and the operating arm 33 may be located where desired. Hence it will be apparent that the lock may be mounted in almost any desired position.

Although I have illustrated and described only 75

one specific embodiment of my invention, it is to be understood that modifications thereof and changes therein may be made without departing from the spirit and scope of the invention.

5 I claim as my invention:

1. A lock for an elevator door comprising a casing, a hook member immovably fixed on the door in position to be moved into the casing by the closing of the door, a locking latch for locking 10 the hook in the casing, a spindle for supporting and operating the latch, a horizontal shaft rotatably mounted in the casing for operating the spindle, an arm attached to the shaft, means for raising the arm to operate the shaft into unlock- 15 ing position, an insulating block mounted above the latch and the hook in the casing, two pairs of spring arm contacts mounted in the block with their lower ends depending near the hook and the latch, a bridging plate mounted on the nose of 20 the hook member in position to engage and electrically connect one pair of the spring arm contacts when the hook member is in its door closed position, a second bridging plate, and means for mounting the second bridging plate 25 on the spindle to cause it to engage and electrically connect the second pair of spring arm contacts when the spindle is operated to move the latch into its locking position.

2. A lock for an elevator door comprising a casing, a hook member immovably fixed on the door in position to be moved into the casing by the closing of the door, a locking latch for locking 5 the hook in the casing, a spindle for supporting and operating the latch, a horizontal shaft rotatably mounted in the casing for operating the spindle, an arm attached to the shaft, means for raising the arm to operate the shaft into unlock- 10 ing position, an insulating block mounted above the latch and the hook in the casing, two pairs of spring arm contacts mounted in the block with their lower ends depending near the hook and the latch, a bridging plate mounted on the nose of 15 the hook member in position to engage and electrically connect one pair of the spring arm contacts when the hook member is in its door closed position, a second bridging plate, and means for mounting the second bridging plate on the spindle to cause it to engage and electrically connect 20 the second pair of spring arm contacts when the spindle is operated to move the latch into its locking position, said arm having sufficient weight to over-balance the spindle, thus causing it to move the latch into locking position when 25 the means for raising the arm is removed therefrom.

HARRY H. VANDERZEE.
